[57] CLAIM

The ornamental design for a combined mixing and filter bowl, as shown and described.

DESCRIPTION

FIG. 1 is a perspective view of a combined mixing and filter bowl showing my new design;

FIG. 2 is a perspective view taken from the top thereof;

FIG. 3 is a top plan view thereof; and

FIG. 4 is a cross sectional view taken on lines 4—4 of FIG. 3.

It is to be understood that the fragmentary showing of filter material is continuous throughout the area indicated in FIGS. 1 through 4.
